UNITED STATES PATENT OFFICE

1,924,681

BOX MACHINE

Theodore A. Federwitz, Philadelphia, Pa., assignor to Stokes and Smith Company, Philadelphia, Pa., a corporation of Pennsylvania

Application March 6, 1931. Serial No. 522,739

15 Claims. (Cl. 93—54)

My invention relates to machines for forming and/or wrapping boxes, and particularly boxes of great depth.

In general, my invention relates to improvements in the box machine disclosed in U. S. Letters Patent 1,541,036 to myself and another, which permit it to be used in wrapping large boxes, and particularly deep boxes, which were previously wrapped only by hand.

More specifically, the operating mechanism for the form-block structure of the machine is so constructed that the great length of travel or stroke of the form block is obtained without corresponding increase in the space necessary for the machine; and preferably, the operating mechanism is substantially wholly contained within the hollow structure or framework of the machine.

Further in accordance with my invention, the mechanism for ejecting the finished boxes is adjustable independently of the box-forming or wrapping instrumentalities to permit of great accuracy of timing of its action.

My invention also resides in the features of construction, arrangement and combination hereinafter described and claimed.

For illustration of a preferred embodiment of my invention reference is to be had to the accompanying drawings in which:

Fig. 1 is a front elevation with parts in section and parts broken away.

Fig. 2 is a side elevation of the machine of Fig. 1 with parts in section and parts omitted.

Fig. 3 is a detail view on enlarged scale of plunger operating mechanism shown in Fig. 2.

Figs. 4 and 5 are plan and front elevational views respectively of the mechanism of Fig. 3.

Fig. 6 is a detail view on enlarged scale of box-ejector mechanism shown in Fig. 1.

Fig. 7 is a detail view of cam mechanism for operating the ejector.

Figs. 8 and 9 are front and side elevational views on enlarged scale of box-stripping mechanism shown in Figs. 1 and 2.

Fig. 10 is a detail view in section of clamping structure for the stripper bars of Figs. 8 and 9.

Referring to Figs. 1 and 2, the pedestal, or base member 1 supports the main frame member 2 of the machine which has a flat table portion 3 and a hollow goose neck column or standard 4. The main operating cam 5 of the machine is disposed within the hollow portion of the frame member 2 beneath its table surface 3, and is clamped or held, as by bolts 6, to the worm gear member 7 disposed within the hollow base or pedestal member 1. The worm gear and cam assembly rests

upon a bearing 8 engaging the upper surface of the lower flange portion of a hollow member 9 secured to the base, as by bolts 10, and extending through the cam assembly and upwardly beyond the top of the table 3. The cam assembly is driven through the worm gear 7 by a worm, not shown, mounted upon shaft 10a which is driven, through the clutch mechanism 11, from any suitable source of power.

A bevel gear 12 secured to or integral with the upper cam clamping member 13 meshes with the bevel gears 14 of the four slide units 15 which are each adjustably clamped, as by bolts 16, flush against the upper surface of table 3. With the bolts 16 unloosened, the slide units may be moved toward and away from each other by rotating the cranks 17 mounted on shafts 18 threadedly engaging the depending slide portions 19. Within each of the slide units, a gear 20 slidably keyed to the shaft 21 upon which a gear 14 is secured, drives a cam 22 for operating the several box forming or wrapping tools, as the presser blocks 23, marginal turn-in fingers 24, turn-in fingers 25, etc. As the top of the table 3 is substantially flush with the bottom of the slide units, these box forming and wrapping tools are very accessible for adjustment or replacement in setting up or changing over the machine for operation upon different sizes of boxes.

Upon one end of lever 26, which is disposed wholly within the hollow frame 2, is mounted a cam follower 27 engaging the lower groove of the main cam 5. The lower end of link 28, which is entirely contained within the vertical or upright portion of the hollow member 4, is connected to the other end of the lever 26 for transmitting movement to lever 29 enclosed by and journaled in, as at 30, the horizontally extending top portion 31 of the goose neck frame. Integral with or preferably secured to the other arm of the lever is a gear segment 32, meshing with pinion 33 rotatable with bevel gear 34 upon a stud shaft 35, as most clearly shown in Figs. 3 and 4. To one end of the shaft 36 is secured the bevel gear 37 for driving the gear 38 which passes through a slot in the outer plunger 46 into mesh with the rack portion 39 of the inner plunger 40. This gear train steps up or multiplies the relatively small movement of the gear segment to effect a long stroke, for example, about 23 inches, of the form-block F, which is sufficient for boxes of depth up to five inches.

The other end of shaft 36 is enlarged and recessed to receive the thrust bearing 41 which is engaged by the adjusting bolt 42.

The guiding member or roller 43 which engages

100

105

110

the slot 44 in the hollow cylindrical member 45 extending vertically at the end of the goose neck member 31, is connected to the inner plunger 40 to prevent any tendency to rotate which would upset the registering relation between the form block structure F and the wrapper applying or box-forming instrumentalities of the slides 15.

The outer plunger 46 is similarly driven from the upper groove of the main operating cam with 10 which engages a cam roller 27' at one end of a lever 26', connected to the link 28'. The length of links 28 and 28' may be adjusted by opening door 28a which affords access to the adjusting members 28b. The upper end of link 28' through 15 a lever and gear train mechanism similar to that described, effects movement of gear 38' with which meshes the rack portion 39' of the outer plunger 46. Any tendency of the outer plunger to rotate is prevented by the guide roller 47 which 20 engages the groove or slot 48 of the vertical cylindrical member 45.

In the construction described, all of the operating mechanism for the inner and outer plungers is completely enclosed, greatly improving the appearance of the machine, decreasing the likelihood of wear and damage, and decreasing the liability of injury to those operating or adjusting the machine. Further, although the machine is constructed to accommodate boxes of substantially greater depth than those heretofore used, with resultant need of a substantially greater path of movement of the form-block structure, the operating mechanism described for the form-block operating plungers obtains the greatly increased 30 operating stroke of the operating plungers without substantial increase in the vertical height of the machine.

Particularly in the forming and/or wrapping of deep boxes, the timing of the ejector for propelling the finished box from the machine is important. When the machine is operating at high speed, the interval for removing the box is very short both in point of time and in respect to the operating cycle. The ejectors previously used were 40 not satisfactory. Referring to Figs. 1, 6 and 7, the housing of one of the slide units is provided with an extending portion 49 for enclosing an additional cam 50 which is rotatable with cam 22, though the relative angular positions of the cams 50 may be varied to time the ejector by loosening nut 51 at the end of the cam shaft and rotating cam 50, as by a wrench or other suitable tool applied to the square end of the cam extension 52 which projects outside of the slide housing. The groove 55 of cam 50 receives a follower 53 at the lower end of a lever 54 which extends upwardly into the interior of the ejector housing 55, mounted upon and secured to the top of the slide.

Referring particularly to Fig. 6, the upper end 60 of lever 54 connects with a tubular member 56, the other end of which is enclosed by a plug 57 forming a shoulder engaging one end of a spring 58 whose other end abuts a shoulder 59 on the ejector rod 60 which passes through the cylindrical member 56 and outwardly from the ejector housing.

The initial movement of lever 54 in counter clockwise direction, as viewed in Fig. 6, compresses the spring 58. Movement of the ejector 70 rod 60 is prevented by the locking members or balls 61 which are wedged between the inclined shoulder 62 of the ejector rod and the inside diameter of the cylindrical member 63. Upon continued movement of lever 54 the cylinder 56 75 engages member 63, moving it to the left, until

the large inside diameter of member 63 comes opposite the locking balls 61, whereupon the spring 58 forces the ball upwardly and forcibly propels the ejector rod 60 forcibly to shove a finished box resting upon the lower form-block structure F' onto the discharge chute 64, preferably mounted upon and adjustable with the opposite slide unit 15.

Upon continued rotation of the cam 50, the lever is swung in a reverse direction, the buffer block 65 at the end of the cylinder 56 engaging the plate or shoulder 66 at the end of the ejector rod to move it to its original position. The member 63 in moving to its original position under the influence of spring 67, returns the locking members or balls 61 to the position indicated in Fig. 6, completing the cycle of operation of the ejector. The spring 68, whose biasing effect upon the lever 54 is adjustable by nut 69, maintains the cam follower in engagement with one side of the cam groove.

By the construction described, the action of the ejector is very rapid, and by provision of the adjustable cam 50, can be accurately timed to occur precisely at the desired point in the operating cycle of the machine.

The outer cylinder 46 in accordance with its known operation, moves downwardly with respect to the inner cylinder to bring the stripper members 70 into position to engage the bottom 105 of the finished box and thus strip it from the form block structure F. In my improved construction shown, the oppositely extending arms 71 of member 72 at the lower end of the outer plunger 46 are of inverted T cross-section. Each 110 of the arms slidably receives a stirrup member 73 through which pass on opposite sides of the arm, the clamping members 74. Each of the clamping members is provided with a head 75 having a hole therethrough which is preferably 115 other than round to receive the horizontal portion of the stripper supporting member 76. The vertical or bent portion of each member or bar 76 is threaded to permit adjustment of a tubular member 77, which contains a spring pressing against 120 the head 78 of the stripper pin 79, adapted to project into the opening 80 of the form block.

Each of the recesses 81 in the stirrups for receiving the heads 75 is of such depth that when the corresponding nut 82 is tightened, the bar 76 125 engages the bottom of the stirrup before the head 75 seats at the bottom of the recess. As the strippers are individually adjustable and each of the strippers can be adjusted without affecting adjustment of the associated stripper, they may 130 be rapidly and precisely adjusted when, for example, it is desired to change from one size box to another. Each stirrup 73 is held in adjusted position by clamping screw 83 (Fig. 10) or equivalent, whose adjustment does not affect the relative positions of the strippers carried by the stirrup.

By the improvements described, the machine is capable of forming large boxes, for example, boxes whose maximum dimensions are of the order of 140 two feet long, fourteen inches wide, and five inches deep. Further the range of sizes of boxes which may be formed or wrapped is increased, for example, boxes whose minimum dimensions are as small as of the order of three-eights of an inch. 145 depth, two and one-half inches width, and four and one-half inches long, may be made with the same machine.

What I claim is:

1. A box machine comprising form block struc- 150

- ture, a supporting member therefor having a rack portion, a cam, and means for transmitting motion from said cam to effect reciprocation of said supporting member comprising a gear segment oscillated in accordance with said cam, and a gear train between said gear segment and said rack portion of said supporting member. 5 80
2. A box machine comprising form block structure, a plunger for supporting said form block structure and having a rack portion, a second plunger having a rack portion, structure carried thereby for stripping finished boxes from said form block structure, cam structure, and mechanisms for effecting reciprocation of said plungers in accordance with said cam structure comprising gear trains terminating in gears engaging the rack portions of said plungers. 10 85
3. A box machine comprising form block structure, concentric plungers for supporting said form-block structure and box-stripping means, both of said plungers having rack portions and the rack portion of the inner plunger opposite an elongated opening in the outer plunger, cam structure, and means for transmitting motion from said cam to effect reciprocation of said plungers comprising gear trains terminating in gears engaging the rack portions of said plungers, the gear directly engaging the rack portion of said inner plunger passing through said opening in said outer plunger. 15 90
4. A box machine comprising a hollow base member, a hollow standard extending upwardly from said base member and having a horizontally extending portion, a reciprocating member having a rack portion and supported from said horizontally extending portion of said standard, form block structure carried by said member, cam structure within said hollow base member, and means for transmitting motion from said cam to said member comprising reciprocating rod structure disposed within the upwardly extending portion of said standard and a gear train disposed in said horizontally extending portion and terminating in a gear engaging said rack portion of said member. 20 95
5. A box-machine comprising vertically reciprocating form-block structure, a supporting member disposed beneath the lower limit of travel of said form block structure and having substantially all of its upper surface in the same horizontal plane, and a plurality of units, each comprising instrumentalities cooperating with said form-block structure during its movement, adjustably mounted on and supported by the upper flat surface of said member for movement toward and away from the path of movement of said form block structure with all of said instrumentalities above said surface and readily accessible for adjustment or replacement. 25 100
6. A box-machine comprising reciprocating form-block structure, a supporting member disposed beneath said form-block structure, a plurality of units, each comprising instrumentalities cooperating with said form-block structure during its movement, adjustable on said supporting member, toward and away from the path of movement of said form-block structure, and a box-discharge chute mounted on and movable with one of said units. 30 105
7. A box-machine comprising reciprocating form-block structure, a supporting member disposed beneath said form-block structure, a plurality of units, each comprising instrumentalities cooperating with said form-block structure during its movement, adjustable on said supporting member, toward and away from the path of movement of said form-block structure, a box-discharge chute mounted on and movable with one of said units. 35 110
8. In a box-machine, movable form-block structure, a unit movable toward and from the path of movement of said form-block structure comprising a cam, mechanism operated thereby for cooperating with said form-block structure, a box-ejecting member, and a second cam rotatable with and angularly adjustable with respect to said first cam for operating said box-ejecting member. 40 115
9. In a box machine, movable form block structure, a box ejector mechanism comprising an ejector member, a spring, an operating member movable to store energy in said spring and to effect release thereof for box-ejecting movement of said ejector member, a shaft rotating in timed relation to movement of said form block structure, and a cam for actuating said operating member angularly adjustable on said shaft to vary the time of release of said ejector member. 45 120
10. In a box machine, form block structure, and means for stripping boxes therefrom comprising a relatively movable member, a second member movable along said first member parallel to the upper surface of said form block structure, means for adjustably clamping said second member to said first member, and a plurality of box stripping members adjustably and independently secured to said second member independently of said clamping means and on opposite sides of said first member. 50 125
11. A box machine comprising form block structure having independent portions, plungers for supporting said portions and having rack portions, common guiding means for said plungers, means carried by said plungers and cooperating with said guiding means to prevent angular displacement of said form block structure, cam structure, and means for transmitting motion therefrom to effect reciprocation of said plungers comprising a gear train terminating in gears supported by said guiding means and engaging the rack portions of said plungers. 55 130
12. In a box machine having form-block structure, a box ejector mechanism comprising a reciprocable member, spring means, operating structure movable to store energy in said spring means, a member having limited movement longitudinally of said reciprocating member, normally preventing movement of said reciprocating member toward the path of said form block structure, and engaged by said structure to release said reciprocable member for actuation by said spring means. 60 135
13. In a box machine having a form block, an ejector mechanism comprising a reciprocable element, spring means, structure operable to tension said spring means for propelling said element toward the path of said form block, locking members for said element biased to released position 65 140 by said spring means when tensioned, retaining means for said locking members adapted to be engaged by said structure, to permit said spring means to release said locking members and actuate said element, and biasing means for said retaining means for restoring said members to locking position upon retraction of said element. 70 145
14. In a box machine having a form block, an ejector mechanism comprising a reciprocable element having a section of reduced diameter form- 75 150

ing a shoulder, locking members, biased structure for holding said members against said shoulder, spring means, structure operable in one direction to tension said spring means, a retaining member for said locking members engaged by said structure upon movement in said one direction to permit said spring means to force said locking members out of engagement with said shoulder, and biasing means for said retaining member operable upon retraction of said element to move said locking members to locking position and to retain them in said position.

15. In a box machine having a form block, an

ejector mechanism comprising a reciprocable element, a stationary tube for guiding said element, locking members for said element projecting through said tube, a member slideable on said tube and adapted to engage said locking members, spring means, operating structure for tensioning said means and adapted to move said slideable member in one direction to effect release of said locking members to permit actuation of said element by said spring means, and means for effecting movement of said slideable element in reverse direction to reset said locking members.
